DESIGN FOR A LAMP BASE OR SIMILAR ARTICLE

Harry M. Laxer, New York, N. Y., assignor to Idealite, Inc., New York, N. Y., a corporation of New Jersey

Application March 19, 1936, Serial No. 61,692

Term of patent 3½ years

To all whom it may concern:

Be it known that I, Harry M. Laxer, a citizen of the United States and a resident of the city, county, and State of New York, have invented a new, original, and ornamental Design for a Lamp Base or Similar Article, of which the following is a specification, reference being had to the accompanying drawing, forming part thereof.

In the drawing, the figure is a perspective view of a lamp base or similar article showing my new design.

The appearance of both sides of the lamp base or similar article is identical.

I claim:

The ornamental design for a lamp base or similar article, as shown and described.

HARRY M. LAXER.
